BLOWING MACHINE FOR INSULATION
AND THE LIKE

Archibald L. Wedebrock, Westwood, N. J., assignee to Johns-Manville Corporation, New York, N. Y., a corporation of New York

Application June 2, 1945, Serial No. 597,303

7 Claims. (Cl. 302—50)

1

The instant invention relates to improved machines for pneumatically conveying insulating materials and the like in particulate form.

At the present time a common method of insulating wall spaces, such as the wall spaces defined by the studding, inner lathing and outer sheathing of frame buildings, resides in pneumatically filling such spaces with a bulk insulating material. A preferred insulating media comprises mineral wool in the form of relatively small aggregates known commercially as nodulated or granulated mineral wool. It will be understood that the term "mineral wool" is used herein in a generic sense to include fibers or fibrous material formed of rock, slag, glass, mixtures thereof, and other suitable raw materials. The filling of the wall spaces is accomplished by a blowing machine comprising a blower, a discharge line into which the bulk insulating material is fed from a suitable hopper, and a hose extending from the discharge line and including a nozzle to be inserted in openings formed in the building wall.

The instant invention is concerned with, and has for its principal object, the provision of an improved blowing machine for use in operations of the kind referred to above. More particularly, an object of the invention is the provision of a blowing machine which achieves an improved automatic feed of insulating material whereby, as compared to prior practice, a steadier discharge is attained and more uniform coverage, i. e., density of the deposited wool, is produced.

Another object of the invention is the provision of a blowing machine including an insulation-receiving hopper and means for feeding the insulation from the hopper to the air conduit, both of an improved design.

My invention will be more fully understood and further objects and advantages thereof will become apparent when reference is made to the more detailed description of the invention which is to follow and to the accompanying drawings in which:

Fig. 1 is a view partially in elevation and partially in section of a blowing machine embodying the instant invention;

Fig. 2 is a top plan view of the apparatus of Fig. 1;

Fig. 3 is a sectional view taken on the line 3—3 of Fig. 2;

Fig. 4 is an end elevational view of the apparatus of Figs. 1 and 2; and

Fig. 5 is a sectional view taken on the line 5—5 of Fig. 1.

2

Referring now to the drawings, there is shown a blowing machine, indicated generally at 10, adapted particularly for use in the installation of an insulating filling in building walls and other wall spaces of a character to receive bulk insulating materials, such as nodulated mineral wool and the like. It will be understood that the machine of the invention is not limited to use with any particular bulk insulating material.

Machine 10 comprises a frame or base 12 suitably made up of I-beams, as shown, joined together to provide a platform for the support of the several elements of the apparatus. Supported on frame 12 is a hopper 14 adapted to receive the material to be blown. Hopper 14 (see particularly Figs. 4 and 5) includes a substantially vertical side wall 16 and an inclined side wall 18 connected at their lower sides by a curved bottom wall 20. Extending from an end wall of the hopper (see Figs. 1 and 3) is a restricted passageway 22 defined by tubular member 24 secured around an opening formed in the end of the hopper adjacent said bottom and vertical side walls. If desired, member 24, at least in part, may be formed integrally with the side and bottom wall elements, or it may be made as a separate member and welded or otherwise secured to the hopper. The end of member 24 remote from the hopper forms one arm of a Y 26 having tubular branches 28 and 30 for a purpose later to be described.

A platform 32 supported from the main frame 12 as by legs 34 carries a blower 36 of any suitable type such, for example, as that known in the trade as a "Root" blower and conventionally used in blowing machines of the type under consideration. A prime mover M, suitably an internal combustion engine as illustrated, is also supported on platform 32 and may be enclosed, as illustrated, by housing 38. The motor M is arranged to drive blower 36 through the intermediary of suitable pulleys and belting, as shown, and through a gear box 40 of any conventional construction which serves to transmit the power from the motor to the blower and other operated parts to drive them at their desired relative speeds. The discharge outlet 42 of blower 36 is connected by means of a flexible hose, or other suitable fitting 44 with branch 28 of Y-member 26. The other arm 30 of the Y-member is connected with a delivery hose 45. Hose 44, branches 28 and 30 and delivery hose 45 together form a discharge conduit leading from the blower to the place of deposit of the insulating material.

Hose 45 is of substantial length so that it may extend from the blowing machine, placed in a suitable location, to the spaces to be insulated and is provided with a nozzle or other fitting (not shown) for insertion in the openings leading into such spaces.

A screw conveyor 46 carried by a shaft 48 extends the length of the hopper adjacent the bottom wall thereof and projects into restricted passageway 22 to a point just beyond the juncture with branch 28, as shown particularly in Fig. 3, the shaft 48 being supported in bearings 50 and 52 carried by posts 51 and 53, respectively, projecting upwardly from the opposite ends of frame 12. A packing gland 54 preferably surrounds shaft 48 at the point where it penetrates the wall of the Y-member (see Fig. 3) to prevent leakage of the flowing air. The diameter of the screw is such that it relatively closely fits the restricted passageway.

A breaker bar, indicated generally at 58, extends longitudinally of the hopper and comprises a shaft 60 carrying a plurality of breaker arms 62. As shown, the alternate breaker arms lie in a common plane at substantially right angles to the common plane of the intermediate breaker arms. In addition, alternate breaker arms preferably extend at an acute angle to the shaft. This construction insures the complete breaking up of enlarged clumps or agglomerations of the material discharged into the hopper during the operation of the machine as will later more clearly appear. Shaft 60 lies above, but laterally offset with respect to, screw conveyor 46 (see Fig. 2). One end of shaft 60 is preferably connected directly into gear box 40 to be driven therefrom, as shown, the other end being supported in bearing 64 carried by post 51. A pulley 66 is keyed on shaft 60 between the end of the hopper and bearing 64. Pulley 66 is in line with a pulley 68 keyed to shaft 48 of the screw conveyor and the pulleys are operatively connected by belt 70 whereby the screw conveyor is driven from the gear box through shaft 60.

In the operation of the apparatus described above, the insulating material in bulk form, such as nodulated mineral wool, is poured or otherwise discharged into hopper 14 to substantially fill the same. Motor M is operated to cause rotation of breaker bar 58 and screw conveyor 46 in the same direction, as indicated by the arrows in Fig. 5. Operation of the motor also causes blower 36 to set up a current of air flowing through hose 44 and arms 28 and 30 of Y-member 26 and into delivery hose 45. Large clumps or agglomerations of the insulating material are broken up by the arms of breaker bar 58 whereby the material in the bottom of the hopper adjacent the screw conveyor is in relatively loose, open, fibrous form. The opened material is forced, by combined gravitational action and the rotation of the breaker bar, into the screw conveyor through the relatively open space 72 along side the conveyor. Rotation of the screw forces the material forwardly through restricted passageway 22 to deposit it in Y-member 26 where it is picked up by the air stream and carried thereby through hose 45 to the place of discharge, suitably a hollow wall space.

The particular construction and design of the hopper and cooperating screw conveyor and breaker bar including the positioning of the screw conveyor and breaker bar in the hopper, all as described above, insures that the conveyor will continuously pick up a full load of the insulating

material and hence maintain the passageway 22 completely filled with the insulating material to prevent any tendency of the flowing air to blow back through the hopper. The Y-connection between member 24 and the air passageway permits the insulating material to be picked up by the air stream in substantial continuation of the forward movement imparted to it by the screw conveyor and, hence, promotes free flow of the same into and with the air stream. The combined result of the features noted is a continuous and uniform flow of the insulating material through hose 45 whereby the density of the deposited insulation may be maintained substantially constant. The feed is entirely automatic, requiring merely the dumping of the wool into the hopper and the insulating material does not have to be pushed into the feeder by hand as is customary in many machines. The construction of the machine provides for long use without excessive wear.

Having thus described my invention in rather full detail it will be understood that these details need not be strictly adhered to but that various changes and modifications may suggest themselves to one skilled in the art, all falling within the scope of the invention as defined by the subjoined claims.

What I claim is:

1. A blowing machine for insulation and the like comprising a hopper having relatively converging side walls, a blower, a discharge conduit leading from the blower, a restricted passageway leading from said hopper and forming a Y-connection with said conduit, a screw conveyor extending substantially the length of said hopper along the bottom thereof and closely adjacent one wall to leave a space between it and the opposite wall, said conveyor projecting into said passageway to deliver material from said hopper to said conduit, and means for rotating the screw conveyor toward said opposite wall.

2. A blowing machine for insulation and the like comprising a hopper having relatively converging side walls, a blower, a discharge conduit leading from the blower, a restricted passageway leading from said hopper in communication with said conduit, a screw conveyor extending substantially the length of said hopper along the bottom thereof and closely adjacent one wall thereof to leave a space between it and the opposite wall, a breaker bar in said hopper, said breaker bar being laterally offset with respect to said screw conveyor and with its axis vertically above said space, said conveyor projecting into said restricted passageway to deliver material from said hopper to said conduit, and means for rotating said breaker bar toward said one wall.

3. A blowing machine for insulation and the like comprising a hopper, a blower, a discharge conduit leading from the blower, a restricted passageway leading from said hopper and forming a Y-connection with said conduit, a screw conveyor extending from said hopper into said restricted passageway to deliver material from said hopper to said conduit, the conveyor defining a space with a wall of the hopper, a breaker bar rotatably supported in laterally offset relationship to the screw conveyor and vertically above said space, and means for rotating said breaker bar toward said wall.

4. A blowing machine for insulation and the like comprising a hopper having a substantially vertical wall and an inclined wall connected by a bottom wall, a blower, a discharge conduit leading from the blower, a restricted passageway

leading from said hopper adjacent said bottom wall and in communication with said conduit, a screw conveyor lying closely adjacent said vertical and bottom walls and spaced from said inclined wall, said conveyor projecting into said passageway, and means for rotating said screw conveyor toward said inclined wall.

5. A blowing machine for insulation and the like comprising a hopper having a substantially vertical wall and an inclined wall connected by a bottom wall, a blower, a discharge conduit leading from the blower, a restricted passageway leading from said hopper adjacent said bottom wall and in communication with said conduit, a screw conveyor lying closely adjacent said vertical and bottom walls and leaving a space between it and said inclined wall, said conveyor projecting into said passageway, a breaker bar extending longitudinally of said hopper vertically above said space and in lateral, offset relationship to said conveyor, said breaker bar including laterally extending breaker arms, and means for rotating the bar toward said inclined wall.

6. A blowing machine for insulation and the like comprising a hopper having a substantially vertical wall and an inclined wall connected by a bottom wall, a blower, a discharge conduit leading from the blower, a restricted passageway leading from said hopper adjacent said bottom wall and in communication with said conduit, a screw conveyor lying adjacent said vertical and bottom walls and leaving a space between it and said inclined wall, said conveyor projecting into said passageway, a breaker bar extending longitudinally of said hopper vertically above said space and in lateral, offset relationship to said conveyor, and means for rotating said conveyor and breaker bar toward said inclined wall.

7. In a hopper for insulation or the like, rela-

tively converging side walls including an outwardly and upwardly inclined wall and a bottom wall connecting said side walls, a screw conveyor extending substantially the length of said hopper, said conveyor being positioned closely adjacent the bottom wall to define a space with said inclined wall, said bottom wall curving from said inclined wall to a point below said conveyor whereby material deposited in said hopper will be delivered by said inclined wall and curved bottom wall laterally to said conveyor and bridging across the conveyor will be prevented, a breaker bar in said hopper, said breaker bar being vertically above said space and laterally offset with respect to said screw conveyor, and means for rotating said breaker bar and conveyor toward said inclined wall.
